(57) **CLAIM**

The ornamental design for insulating sleeve, as shown and described.

DESCRIPTION

FIG. 1 is a perspective view of the insulating sleeve showing a new ornamental design thereof;

FIG. 2 is a front view of the insulating sleeve shown in FIG. 1;

FIG. 3 is a back view of the insulating sleeve shown in FIG. 1; FIG. 4 is a right side view of the insulating sleeve shown in FIG. 1;

FIG. 5 is a left side view of the insulating sleeve shown in FIG. 1;

FIG. 6 is a bottom view of the insulating sleeve shown in FIG. 1; and,

FIG. 7 is a top side view of the insulating sleeve shown in FIG. 1.

The broken lines shown in the drawings are understood to represent stitching.
